UNITED STATES PATENT OFFICE.

ELVERTON I. HOWARD, OF WESTFIELD, NEW YORK; ELSIE R. HOWARD EXECUTRIX OF SAID ELVERTON I. HOWARD, DECEASED; ALEXANDER THOMPSON EXECUTOR OF SAID ELSIE R. HOWARD, DECEASED; SAID ALEXANDER THOMPSON, EXECUTOR, ASSIGNOR TO PRIMOLITE COMPANY, OF INDIANAPOLIS, INDIANA.

LENS-HOLDER FOR HEADLIGHTS.

1,344,695.

Specification of Letters Patent. Patented June 29, 1920.

Application filed September 18, 1919. Serial No. 324,266.

To all whom it may concern:

Be it known that I, ELVERTON I. HOWARD, a citizen of the United States, residing at the village of Westfield, in the county of 5 Chautauqua and State of New York, have invented certain new and useful Improvements in Lens-Holders for Headlights, of which the following, taken in connection with the accompanying drawings, is a specification.

The invention relates to improvements in headlights for vehicles, and is an improvement on the construction shown in my application for Letters Patent filed July 25, 15 1919, Ser. No. 318,254; and the improvement consists in providing a frictional holding means attached at spaced intervals to the lens itself either on the front or rear sides so that when said lens is placed in the 20 lamp, said frictional holding means will keep the lens from turning or being moved out of an adjusted position in said lamp by the constant joggling and shaking or other jars from a moving vehicle, and being attached to or a part of the lens itself, said lens can be shipped or otherwise handled without danger of dislodgement of said holding means; and the invention consists in the novel features and combinations hereinafter set forth and claimed.

In the drawings, Figure 1 is an elevation of the front of the headlight with a refracting lens therein held at a plurality of points, preferably three, by the improved holding means, the rim being broken away at the three points for said holding means for the front side, and also being broken away at three other points for the use of said holding means on the rear side of said lens, the 35 disk shaped holding means on the rear side being shown in dotted outline through said lens. Fig. 2 is a sectional view at line 2-2 in Fig. 1 of one form of lamp rim, showing the frictional holding means or disk on the 40 front side of the lens. Fig. 3 is an elevation of a portion of the lens, and may be taken for either a rear or a front view, that is, at either line 5-5 or line 2-2 in Fig. 1, showing the cavity in the edge portion of said 45 lens with the same shaped resilient lens holder or disk at one side ready to be in-

serted in the cavity. Fig. 4 is a sectional view of the edge portion of the lens at line 2-2 in Fig. 1 showing in slightly enlarged form the holding disk in the front of the 55 rim portion of the lens as in Fig. 2; and Fig. 5 is a sectional view at line 5-5 in Fig. 1 showing the resilient lens holder in the rear side of said lens.

Like characters of reference refer to corresponding parts in the several views.

The numeral 10 designates the lens which is made of cast glass with the prismatic or other diffusing means or formations therein and the edge or rim portion 11 extending 65 around the same.

In order to fit said lens to the many different forms of lamps now on the market so as to adapt the lens holding means to all of the different constructions of lamp rims, 70 a plurality of cavities 12 on the front side and 13 on the rear side are pressed or cast into the glass lens 10 at spaced distances from one another, preferably equi-distant and three in number on each side. Said 75 cavities are preferably disk shaped though they may be any other desired shape without departing from my invention.

The lens holding disks or blocks 14 are provided which fit interchangeably within 80 the cavities 12 or 13 so that they may be changed to fit any form of lamp rim and hold the lens 10 firmly thereunder. The lens holding disks or blocks 14 are preferably made of good resilient rubber of the quality 85 called self-vulcanizing which adheres of itself to the glass within the cavities 12 or 13. They are preferably about three-eighths inch in diameter by about one-eighth inch in thickness and slightly larger than the cavities 12 or 13 so as to need compression into 90 said cavities in order to insert the same to thereby hold them firmly in position in the lens 10 during shipment and installation. When so compressed into the cavities 12 or 95 13, the disks 14 act as additional packings which prevent the lens 10 from turning or being moved from an adjusted position. The metal rim 15 of the headlight which is attached to the reflector 16 compresses the 100 lens 10 and the holding disks 14 against the packing 17 on the rim of the reflector 16 if

on the rear side, or against the rim 15 if on the front side.

In order to insure the firm holding of the lens 10, the lens holders or resilient disks 14 are arranged for insertion in the cavities 12 or 13 on either the front or rear sides of said lens 10 according to the construction of the lamp rim. The lens 10 is mounted by placing one holding disk 14 at the exact vertical center of the rim of the reflector 16, in which position said lens will be mounted so that the crosswise prisms or other light diffusing means will refract the light on the roadway in perfect alinement 15 as designed.

It is apparent that the cavities 12 and 13 may be cast or pressed in the lens at the time that it receives its prismatic or refracting formations, and that the round disks or 29 holding blocks 14 may be pressed into the cavities 12 and 13 thereby removably holding said disks firmly therein for shipment and installation of said lens 10 in the lamp. Though the invention is simple, it performs 25 its office as a resilient holding means for the lens 10 so that said lens cannot be joggled out of position or turned when installed in the lamp, at the same time providing a splendid cushion for the glass lens 3: whether said disks 14 are pressed against the packing 17 at the rear of the lens, or against the inner side of the rim 15 of the reflector 16 on the front. It is also obvious that more than three of said spaced resilient 35 lens holders may be used around the periphery of the lens 10 on either side if deemed advisable, though it has not been found

necessary for lenses of the average weight and design.

I claim as new:

1. A headlight comprising a reflector, a lens for the front of said reflector, a metal rim to hold said lens around the outer edge portion thereof, said outer edge portion having cavities therein, and resilient rubber 45 blocks attached in said cavities to frictionally hold said lens from turning when under pressure of said rim.

2. In a lamp for vehicles, a reflector, a lens for the front of said reflector having a plurality of spaced cavities in the edge portion thereof, a packing between said lens and said reflector, an attaching rim for the outer side of said lens around the edge portion thereof, and resilient retaining blocks 55 attached in said cavities to be compressed by said attaching rim to hold said lens from turning.

3. In a vehicle lamp, a reflector, a lens for the front of said reflector having a plurality of disk shaped cavities in both sides of the edge portion thereof, a plurality of resilient disk shaped holding elements removably attached in said disk shaped openings, and a metal holding rim 65 attached to said reflector to compress said holding elements and prevent said lens from turning.

In testimony whereof I have affixed my signature in the presence of two witnesses.

ELVERTON I. HOWARD.
